MOP

Henry Cave, Hartford, Conn., assignor to The Fuller Brush Company, Hartford, Conn., a corporation of Connecticut

Application March 6, 1933, Serial No. 659,763

9 Claims. (Cl. 15—147)

My invention relates to that class of cleaning utensils which are employed more particularly for brushing purposes, and an object of my invention, among others, is the production of a 5 mop which is simple in construction, convenient for use and especially efficient in the results obtained from such use.

Forms of mops embodying my invention and in the construction and use of which the objects 10 herein set out, as well as others, may be attained is illustrated in the accompanying drawing, in which—

Figure 1 is a plan view of my improved mop frame.

15 Figure 2 is an edge view of the same.

Figure 3 is a side view of the complete mop.

Figure 4 is a view in section on a plane denoted by the dotted line 4—4 of Fig. 1.

Figure 5 is a plan view of my improved mop 20 frame in a little different form.

Figure 6 is an edge view of the same.

Figure 7 is a plan view of the complete mop.

Figure 8 is a plan view of the mop frame in a 25 still different form.

Figure 9 is an edge view of the same.

Figure 10 is a view on enlarged scale in cross section through the pivotal supporting bar on a plane denoted by the dotted line 4—4 of Figure 1, but looking in the opposite direction.

30 Figure 11 is a view on enlarged scale of a portion of said bar looking toward the edge of the frame of which it forms a part.

My improved mop contemplates a frame or support and a mop or swatch in the form of a 35 pad with cleaning material of a fibrous character, which may consist of threads, wool or other soft substance comprising its cleaning face, said pad having a pocket for the reception of said frame or support, the latter being preferably composed 40 of wire bent to suitable shape and foldable for insertion in said pad and having means for securing it in unfolded position in said pocket to maintain the pad more or less rigid for cleaning purposes.

45 My improved supporting frame is readily embodied in different forms for mops of the same type and also for mops of different types, that is, in mops especially adapted for use in cleaning articles of furniture and the like, or for brushing 50 walls, floors and other similar surfaces, the former type being smaller than the latter and having comparatively short handles, although it will be understood that my invention may be embodied in mops of various types and applied for 55 various purposes.

As to the frame of the smaller type I have shown in the drawing herein two of several different forms that may be employed, both being of the same general shape but differing as to construction. That shown in Fig. 1 comprises a 5 frame member 10 of substantially rectangular shape and composed of wire with overlapped ends 11 on one side, said ends overlapping to a substantial extent and being secured together in any suitable manner as by welding. A holder 10 of U-shape, and also composed of wire, is secured to one of the overlapped ends, as by welding the base 12 to said overlapped ends. The arms 13 of this holder are outturned at their ends to form catches 14 which may be in the 15 shape of hooks. A retainer of wire comprising a base 15 is secured to an overlapped end, the ends of said base being outturned to form retaining lugs 16, as shown in Fig. 1.

A second frame member 17, also composed of 20 wire, is pivotally attached to the frame member 10 and is preferably of flat-iron shape. Each branch 18 thereof is formed with retaining notches 19 to receive the catches 14. Loops 20 at the ends of the branches 18 are engaged with 25 a side of the frame 10 to pivotally connect the two frame members, the loops being slidable along the frame 10 to permit the branches 18, by their resiliency, to be engaged with and disengaged 30 from the catches 14.

The two overlapped ends 11 and the bases 12 and 15 of the holder and retainer are all rigidly secured together, and all being of the same size of wire, they present a substantially square shape in cross-section, thereby constituting a supporting bar 21 for a handle 22 that is secured to the bar as by means of a connector 23. This connector is preferably composed of two pieces of metal stamped to shape with a handle socket between them and an opening at their outer ends 40 to receive the supporting bar 21. This opening is of substantially square shape to correspond to the cross-sectional shape of the bar 21, diagonally opposite corners of the opening being adapted to receive diagonally disposed members of said 45 bar. The two parts comprising the end 24 of the connector are somewhat resilient and said diagonally disposed members of the bar constitute detents to yieldingly hold the handle in different positions for use.

A swatch or mop 26 comprises a pad 27 having pockets at opposite ends with an opening 28 between them to receive the frame hereinbefore described, which frame is inserted in a somewhat folded position, and then being straightened the 55

catches 14 are engaged with the notches 19 by pressing the branches 18 toward each other and then allowing them to spring apart to engage the catches, thereby locking the members of the 5 frame in an extended position.

The structure shown in Figs. 5 to 7 is of the same general form as that just described, the main difference being in the manner of forming the catches for locking the frame members in 10 extended positions. In this structure the opposite ends of the wire comprising the frame members are twisted together, preferably by applying a twisting force at the center 29, thereby forming two oppositely twisted ends 30 comprising the 15 support for the connector for the handle. The extremities of these ends are extended into arms 31 terminating in catches 14 to engage the notches 19 in the frame member 17 which is of substantially the same flat-iron shape as hereinbefore described.

My improved frame shown in Figs. 8 and 9 is designed more especially for floor or wall uses, as by means of a long handle. The two frame members 32 and 33 are of substantially rectangular 25 shape and are composed of wire as hereinbefore described. The frame member 32 has its ends twisted together, as at 34, at the crosswise center of the frame and the extremities are then bent laterally as at 35 and the ends are bent into 30 catches 36 to interlock with the side parts of the frame member 33. This member 33 has the ends of its sides 37 formed into loops 38 which receive the end 39 of the frame member 32, and as shown in Figs. 8 and 9 of the drawing. The sides 37 are 35 sprung together to engage them with the catches 36, in the manner hereinbefore described with respect to the structures of the other figures of the drawing.

The structures first herein described are intended for use by moving them back and forth in a direction lengthwise of the implement, whereas the mops embodied in the structures of Figs. 8 and 9 are designed for use by movement back and forth in a direction crosswise of the structures. The former therefore have the supporting 45 bars for the connector extended crosswise of the structures while the latter has the supporting bar 34 extended lengthwise of the structure. It will be understood that the swatch or mop to receive the frame shown in Figs. 8 and 9 is of a 50 shape to correspond to that of the frame members with two pockets to receive said members that are inserted in the same manner as hereinbefore described with respect to the structures of Figures 55 1 to 7.

I claim:

1. A mop frame comprising two frame members formed of wire, one of the frame members being of substantially rectangular form and closed 60 at the four sides thereof and composed of a single strand of wire, one side of said frame member composed of said wire constituting a pivot element, a cooperating frame member of substantially U-shape having a loop at the free end of each side leg thereof pivotally supported on the pivot element of the rectangular frame member respectively adjacent opposite ends thereof, and means rigidly carried by the pivot element of the rectangular frame engageable with the side legs 65 of the U-shaped frame for holding the two frame members in the same plane.

2. A mop frame comprising two frame members formed of wire, one of the frame members being of substantially rectangular form and closed at 70 the four sides thereof and composed of a single

strand of wire, one side of said frame member composed of said wire constituting a pivot element, a cooperating frame member of substantially U-shape having a loop at the free end of each side leg thereof pivotally supported on the 5 pivot element of the rectangular frame member respectively adjacent opposite ends thereof, and angular catch members rigid with the pivot element of the rectangular frame and angularly disposed relative to said pivot element and then 10 extended for engagement with the side legs of the U-shaped frame for holding the two frame members in the same plane.

3. A mop frame comprising a substantially flat frame member of substantially rectangular form 15 and composed of wire and having a connecting end consisting of overlapped parts of the frame, a catch base secured to one of said parts, said base and overlapped parts constituting a cross-sectional angularly shaped supporting bar, a 20 second substantially flat frame member composed of wire pivotally attached to the first mentioned frame member to be opened out flatwise as an extension of the other frame member, and means extending from said catch base for holding said 25 frame members in said extended position.

4. A mop frame comprising a substantially flat frame member composed of wire and having a connecting end consisting of overlapped meeting ends of said wire, a catch base comprising a piece 30 of wire extending lengthwise of and secured to one of said overlapped ends, a retainer base also composed of wire extending lengthwise of and secured to the other of said overlapped ends and extending alongside of said retainer base, said 35 bases and overlapping ends constituting a cross-sectional rectangularly shaped supporting bar to be received in a similarly shaped opening in a handle connector, a substantially flat frame member pivotally attached to the first mentioned 40 frame member to be opened out as an extension of the first mentioned frame member, means projecting from one of said bases for holding said frame members in said extended positions, and retaining lugs projecting from the other of said 45 bases to limit the swinging movement of one frame member relatively to the other.

5. A mop frame including a rectangular frame member formed of a single strand of material having overlapped ends at one side twisted together to form a supporting bar parallel with the opposite side of the frame member, a second frame member pivotally attached to the supporting bar of the first named frame member to be opened as an extension of the first named frame 50 member, and means rigid with and projecting from each end of the supporting bar for holding said frame members in extended position.

6. A mop frame including a rectangular frame member formed of a strand of material having 60 overlapped ends at one side twined together to form a supporting bar parallel with the opposite side of the frame member, said ends beyond the twisted part projecting laterally of the supporting bar in parallelism, and said ends having their 65 extremities extended substantially parallel to said supporting bar to form catches, and a second frame member pivotally attached to the supporting bar and having resilient sides to engage said catches.

7. A mop frame comprising two substantially flat frame members, one of said members being of substantially rectangular shape and composed of a single piece of wire, the ends of which extend past each other on one side of the frame 75

to create a supporting bar projecting lengthwise along said side, said ends being twisted together to form said bar and the ends beyond the twisted portion being extended laterally to form catches 5 and the other of said frame members being composed of wire with resilient sides for engagement with said catches, the ends of the wire comprising said sides being looped around said supporting bar for pivotally uniting said frame members.

10 8. A mop frame including a frame member formed of a strand of material having end portions meeting at one side to form a supporting bar, said meeting ends being twisted together to 15 extend laterally from said supporting bar and the ends of said strand beyond the twisted por-

tion being projected laterally to form catches, and a second frame member pivotally attached to the supporting bar and having resilient sides to engage said catches.

9. A mop frame including a frame member 5 formed of a strand of material bent to form a rectangular frame with a supporting bar at one side, the ends of said strand being joined in said bar and extended from and beyond said bar and twined together to unite the strands and the extreme ends being extended laterally of the twined portion to form catches, and a second frame member pivotally attached to the supporting bar and having resilient sides to engage said catches. 10
